Primary Examiner — Joseph Kukella

(57) **CLAIM**

The ornamental design for a climbing structure, as shown and described.

DESCRIPTION

Fig. 1.1 is a perspective view of our new design for a climbing structure.

Fig. 1.2 is a front view of 1.1.

Fig. 1.3 is a back view of 1.1.

Fig. 1.4 is a left view of 1.1.

Fig. 1.5 is a right view of 1.1.

(Continued)

Fig. 1.6 is a top view of 1.1.

Fig. 1.7 is a bottom view of 1.1.

2.1 the features shown in broken lines in the drawings depict environmental subject matter only, and form no part of the claimed designs
